US0D1106151S

(12) **United States Design Patent** (10) **Patent No.:** **US D1,106,151 S**
(45) **Date of Patent:** **** Dec. 16, 2025**

(54) **PORTABLE DISPLAY DEVICE**

(71) Applicant: **LG DISPLAY CO., LTD.**, Seoul (KR)

(72) Inventors: **Hyungju Kwon**, Paju-si (KR);
Sangjoon Choi, Paju-si (KR)

(73) Assignee: **LG DISPLAY CO., LTD.**, Seoul (KR)

(**) Term: **15 Years**

(21) Appl. No.: **29/939,675**

(22) Filed: **Apr. 29, 2024**

(30) **Foreign Application Priority Data**

Oct. 30, 2023 (KR) 30-2023-0042481
